DESIGN FOR A COMBINATION BRUSH AND MIRROR

Eugene L. Tourigny, Leominster, Mass., assignor to United Comb and Novelty Company, Inc., Leominster, Mass., a corporation of Massachusetts

Application November 9, 1936, Serial No. 65,811

Term of patent 3½ years

To all whom it may concern:

Be it known that I, Eugene L. Tourigny, a citizen of the United States, residing at Leominster, in the county of Worcester and State of Massachusetts, have invented a new, original, and ornamental Design for a Combination Brush and Mirror, of which the following is a specification, reference being had to the accompanying drawing forming part thereof.

Fig. 1 is a front view of a combination brush and mirror showing my new design;

Fig. 2 is a rear view thereof;

Fig. 3 is an end view thereof; and

Fig. 4 is a fragmental side view with a portion of the article broken away for convenience of illustration.

I claim:

The ornamental design for a combination brush and mirror as shown and described.

EUGENE L. TOURIGNY.
